AUTOMATIC CONTROL FOR WASHING MACHINES

Phillip M. Pappas, Houston, Tex.

Application July 19, 1944, Serial No. 545,586

6 Claims. (Cl. 200—53)

1

This invention relates to an automatic control for washing machines.

An object of the invention is the provision of novel and efficient means for easily controlling and timing the thorough washing of dishes and the like.

Another object of the invention is to equip a standard dishwashing machine with novel means for timing the washing and the rinsing of the dishes or the like.

A further object of the invention is the provision of novel and efficient means that is set for action when the door of the dishwashing machine is in its open position, and then when the dishes are placed in the machine and the door closed, the washing will automatically proceed for a predetermined length of time, and then the washing action will be stopped, whereupon the rinsing is automatically accomplished for a predetermined time, whereupon the dishes are thoroughly cleaned and sterilized.

This application discloses certain improvements over the structures disclosed in my two prior applications for U. S. patents, to wit: "Dish washing machine", filed June 29, 1943, Ser. No. 492,765, and "Timing device", filed June 29, 1943, Ser. No. 492,766.

With the foregoing and other objects in view, my invention comprises certain novel constructions, combinations, and arrangements of parts as will be hereinafter fully described, illustrated in the accompanying drawings, and more particularly pointed out in the appended claims.

In the drawings:

Figure 1 is a view in side elevation of a dish washing machine showing my invention attached thereto, while

Figure 2 is a front view thereof.

Figure 3 is an enlarged vertical sectional view taken on line 3—3, Figure 2 and looking in the direction of the arrows.

Figure 4 is an enlarged vertical sectional view taken on line 4—4, Figure 3 and looking in the direction of the arrows.

Figure 5 is an enlarged sectional view taken on line 5—5, Figure 3 and looking in the direction of the arrows.

Figure 6 is an enlarged sectional view taken on line 6—6, Figure 1 and looking in the direction of the arrows.

Figure 7 is an enlarged perspective view of the upper or primary trigger device.

Figure 8 is an enlarged perspective view of the lower or auxiliary trigger device.

Figure 9 is an enlarged sectional view taken

2

on line 9—9, Figure 8 and looking in the direction of the arrows.

Figure 10 is a detail perspective view of a portion of the door and arm carried thereby.

Figure 11 is an end view of the upper or primary trigger device.

Figure 12 is an enlarged sectional view taken on line 12—12, Figure 2 and looking in the direction of the arrows.

Figure 13 is an enlarged sectional view taken on line 13—13, Figure 11 and looking in the direction of the arrows.

Figure 14 is a vertical sectional view through the lower end of the piston and the valve construction thereof.

Figure 15 is an enlarged vertical sectional view through the guide bearing of the cylinder.

Figure 16 is a vertical sectional view through the cylinder showing a modified form of control means for the piston thereof, for providing precise adjustment of timing without taking the cylinder apart.

Referring to the drawings, in which the preferred form of this invention is illustrated, 25 designates a washing machine, which is provided with a vertically movable door 2 and with a motor 3. My invention comprises a casing 4 in which is positioned a cylinder 5 that rests upon the bottom of said casing 4. A piston 6, preferably in the nature of a rod-like unit, slides through the guide bearing 7 which is on the top of cylinder 5. This guide bearing is externally screw threaded, and is provided with a spiral-like groove 8 which permits oil accumulating in the portion 9 to pass down and into the cylinder 5, Fig. 15.

The piston 6 is provided with a ball 10; this ball is provided with an upper bevelled portion 11 and a lower bevelled portion 12, for the purpose hereinafter described. I use the term "ball" in a broad sense, meaning any like element performing similar functions. The ball is secured in an adjusted position upon piston 6 by means of the screw 13 (Fig. 4).

An upper or primary trigger device is mounted in the upper part of casing 4 and comprises a horizontal rod 14 that has its ends journalled in bearings 15, Fig. 3. Integral with rod 14 is a flat elongated body 16 that has at one end an outwardly-extending horizontal

50 arm 17 and at its other end a depending finger 18. On finger 18 is a screw 19 that has a head 20, Fig. 4, for contacting the button 21 of switch 22. Screw 19 has a lock collar 23 (Fig. 11) whereby the screw can be adjusted to a nicety for accomplishing an efficient result. An integral

bracket 24 depends from the under face of body 16 and an adjustable rod-like tit 25 extends through said bracket 24. A screw 26 is provided for securing the tit in an adjusted position upon said bracket. The outer end of the tit rides over the ball 10. When the device is in its set position, the tit engages the lower bevelled surface 12, Fig. 4, holding the device in its set position, which position is obtained by raising the door 2; this door is slidably connected to piston 6 by an angular arm 27, as will be clearly seen upon referring to Figures 6 and 10. When the door is raised to its full open position, the sleeve-like portion 28 of arm 27 will engage lock collar 29 that is in an adjusted position near the upper end of the piston 6; thus as the door 2 is raised the piston 6 will be raised in the casing 4 until the outer end of the tit 25 rests in the position shown clearly in Figure 4. In this locked position the ball 10 is held until the door is closed, causing the upper end of rod 30 to be engaged by arm 27 (Fig. 10), whereupon the downward pressure exerted upon rod 30 will cause the fixed collar 31 to depress coil spring 32 against bracket 33, permitting the primary trigger device to swing downwardly, thus clearing tit 25 from the ball 10 which allows the piston to move slowly downwardly. When the primary trigger device moves downwardly, finger 18 will be sprung inwardly, whereupon the head 20 of screw 19 will press inwardly on the button 21, closing the circuit in switch box 22 and causing motor 3 to operate. This operation means that the dish washing is taking place in the machine 1. This dish washing action continues until the ball 10 contacts the auxiliary horizontal finger 34 of the lower or auxiliary trigger device, Fig. 8. The auxiliary finger is mounted upon the vertical rod 35 and is held in an adjusted position by screw 36, Fig. 9. On the upper end of vertical rod 35 is a primary finger 37. When the ball contacts finger 34, swinging it slightly, this movement will cause the outer end of finger 37 to actuate the button 38, Fig. 4, whereupon the circuit will be broken and the motor will stop the washing action. Then the ball 10 will be engaging the roller 39, Fig. 1, which is rotatably mounted on the inner end of arm 40; this arm 40 is pivotally mounted at 41 on bracket 42 of the rinsing valve 43. After the roller 39 has passed over the bevelled surface 12 of ball 10, the valve 43 is open, and as the roller 39 travels over the central portion of ball 10, which is unbevelled, the rinsing and sterilizing of the articles, such as dishes, in the machine 1 is taking place. It is to be understood that valve 43 is provided with a valve plunger 44, which is contacted at its outer end by adjustable screw 45 that is mounted upon the rocking arm 40. Thus it will be seen that when the arm 40 is pushed down by the ball 10 that valve plunger 44 will be depressed, whereupon the valve will be opened, permitting the water to be discharged into the machine 1, for the rinsing and sterilizing action.

The inner end of the rod-like piston 6 is provided with a compartment 46 (Fig. 14) which is open at its lower end. Auxiliary ports 47 are formed in the piston 6 together with ports 48. The exterior of the piston 6 is screw threaded at this portion and on this screw threaded portion is an adjustable collar 49. An adjustable sleeve 50 is threaded upon the lower end of the piston 6; this sleeve 50 is provided with an annular flange 51 against which one end of coil spring 52 bears, whereas the other end bears against the under face of the head or disc 53; this disc 53 is slidably

4
5 mounted on sleeve 50. When the piston 6 is moving downward, the disc 53 will be against the collar 49. In this position the oil in cylinder 5 will have to pass up through sleeve 50 into compartment 46 and through ports 48. Thus the downward movement of the piston 6 is slow, being timed to suit the washing action in machine 1. If the operator desires to increase the downward movement of piston 6, he can accomplish this result by means of the structure shown in the embodiment in Figure 16. A pipe 54 is placed on the cylinder 5 with its lower end communicating with the lower portion of the cylinder and its upper end communicating with the interior of the cylinder above the disc or piston head 53. A valve 55 is placed on pipe 54 whereby the operator can control the flow of oil as desired.

It will be understood that the amount of oil discharged through the ports 48 can be controlled by the operator screwing or rotating the collar 49 to cause it to move upwardly, whereby ports 48 can be partly closed or covered to reduce the amount of oil to be passed therethrough. When the piston 6 is in its lowest position within cylinder 5 and the operator pulls upwardly on the piston, disc 53 will move downwardly against the action of spring 52 clearing port 47 which allows the oil above the disc 53 to pass through this port as well as ports 48, hastening the raising of the piston 6, either by manual exertion directly thereon, or by reason of raising door 2.

When the ball unit 10 is in its upper or set position the arm 17 of the primary trigger device will be resting against the fixed collar 31 and said primary trigger device cannot move or swing downwardly until the rod 30 is pushed inwardly. Therefore, when in the set position, as clearly illustrated in Figures 3 and 4, the machine is inactive, but is ready to operate immediately upon the closing of door 2. In other words, the action of the machine is entirely automatic, whereby the closing of the door results in the starting of the motor for the washing action to be followed by the stopping of the motor and the actuating of the valve for permitting the rinsing and sterilizing action of the articles in the machine 1.

Any oil on the piston 6, above the cylinder 5, can run down and pass into the cylinder as explained hereinbefore and illustrated particularly in Figure 15.

It is to be understood that the auxiliary trigger device is pivotally mounted on brackets 56, Fig. 4. Suitable bearings are provided on these brackets 56 for retaining the vertical rod 35 in an efficient operating position.

While I have described the preferred embodiment of my invention and illustrated the same in the accompanying drawings, certain minor changes or alterations may appear to one skilled in the art to which this invention relates, during the extensive manufacture of the same and I, therefore, reserve the right to make such alterations or changes as shall fairly fall within the scope of the appended claims.

What I claim is:

1. In an automatic control for washing machines, the combination of a casing, a cylinder in said casing, a plunger on said cylinder, a ball unit on said plunger, a primary trigger device in said casing and normally engaging said ball unit when said plunger is in a set position, an auxiliary trigger device in said casing and being operated by said ball unit, and a manually operated lock on said casing for normally holding the primary trigger device against action.

2. In an automatic control for washing machines, the combination of a casing, a timing device in said casing including a plunger, a primary trigger device in said casing, said plunger provided with means normally engaging said trigger device when said plunger is in a raised condition, a vertically slideable rod extending through a portion of said casing, a bracket in said casing with the inner end of said rod working therein, said rod provided with a fixed collar normally bearing against a portion of said primary trigger device, a spring on said rod between said bracket and fixed collar, switch means associated with said casing, a rinsing valve associated with said casing, and said switch means and rinsing valve and plunger provided with means whereby when the plunger moves to predetermined positions, said switch means and rinsing valve will be successively operated.

3. In an automatic control for washing machines, the combination of a casing, a cylinder provided with a plunger in said casing, a ball on said plunger, a switch on said casing, a rinsing valve on said casing, a primary trigger device in said casing and provided with means for engaging and holding said ball in a fixed position and with means also for engaging and initially operating said switch, an auxiliary trigger device in said casing, said rinsing valve provided with an actuating arm extending into said casing and in the path of movement of said ball, and said ball of the plunger being adapted to operate said auxiliary trigger device to actuate a switch for stopping a motor and then operate said actuating arm of the rinsing valve.

4. In an automatic control for washing machines, the combination of a hydraulic timing device including a primary trigger device, said trigger device comprising a rod having a flat body extending therefrom, said body provided at one end with an outwardly extending arm, and at its opposite end with a depending finger, said body provided with an integral depending bracket, an adjustable rod-like tip in said bracket, and said depending finger provided with an adjustable screw having a head on its inner end.

5. In an automatic control for washing machines, the combination of a casing provided with a cylinder and a sliding piston thereon, a plurality of trigger devices in said casing, said piston pro-

vided with means operating said trigger devices, a valve provided with a portion extending into said casing, said piston being adapted to operate on said extended portion of the valve, and locking means for one of the trigger devices for positively holding it in a set position.

6. In an automatic control for washing machines, the combination of a hydraulic timer provided with a primary and an auxiliary trigger device, a valve, locking means for said primary trigger device, and plunger means cooperating with said primary trigger device and positively operating said auxiliary trigger device and said valve.
